Attorney.

UNITED STATES PATENT OFFICE.

EUGENE J. LE CLAIRE, OF ST. PAUL, MINNESOTA.

SUPPLEMENTAL TABLE-TOP.

1,203,752.

Specification of Letters Patent.

Patented Nov. 7, 1916.

Application filed October 22, 1915. Serial No. 57,241.

To all whom it may concern:

Be it known that I, EUGENE J. LE CLAIRE, a citizen of the United States, residing at St. Paul, in the county of Ramsey and State of Minnesota, have invented a new and useful Improvement in Supplemental Table-Tops, of which the following is a specification.

This invention relates to certain new and 10 useful improvements in supplemental table tops, the object of this invention being to provide a novel form of table top, which can be easily and quickly secured to different sizes of tables, whereby a table of larger dimensions is produced, which can be readily used 15 for various purposes.

With this and other objects in view, my invention comprises the features of construction and combination of parts hereinafter 20 more particularly described and claimed.

In the drawing, Figure 1 is a plan of my invention when applied to a table; Fig. 2 is a section taken upon the line X—X of Fig. 1; Fig. 3 is a section taken upon the 25 line Y—Y of Fig. 1; Fig. 4 is a perspective of one of the clamps, and Fig. 5 is a section of a detail illustrating a table top when used without an extra leaf.

In carrying my invention into use, the 30 supplemental table top is made of suitable dimensions, and configuration, the table top in the present instance having a curved edge and when used with an extra leaf resembling an oval. When used without the extra leaf 35 it is substantially circular. The table top as illustrated has two end sections 2 and 3, the contiguous edges 4 and 5 of which have mated grooves and tongues respectively 6 and 7. The grooved element 6 (see Fig. 5) 40 is in the form of a strip 8 secured along the edge of the section 2 below its surface, such as by gluing or the use of nails, screws or other fastening means as desired. The tongue member 7 is also in the form of a 45 strip 9 fastened to the lower surface of the top section 3, along the edge 5 in the same manner as strip 8. When the sections of the top are closed and joined together, the tongue and groove coincide and assist in 50 forming a tight joint between the parts.

When an extra leaf such as 10 is employed between the sections 2 and 3 of the top, (see Fig. 2), said leaf is also provided with tongue and groove elements 11 and 12 constructed in the same manner as described and 55 secured along the meeting edges of the leaf

to perform the same function as described. An additional reinforcement is also employed between the sections 2 and 3 of the top or between said sections and the extra leaf, said extra reinforcement consisting of a cleat 13 secured to the lower surface of section 2 and disposed centrally with a projecting tongue 14 extending from the edge 4. A corresponding cleat 15 is suitably secured 65 to the lower surface of section 3 and is also provided with a projecting end or tongue 16. The projecting ends 14 and 16 are adapted to intermesh when the sections 2 and 3 are joined together without an interposed leaf 70 such as 10, said projecting ends fitting in corresponding recesses 17 in the oppositely disposed members 13 and 15. The adjacent side edges of the projecting members 14 and 16 have a tongue and groove connection, such 75 as 18 (see Fig. 3), the parts of which overlap sidewise, but permit longitudinal sliding of the parts together to form a close joint. The extra leaf 10 is provided with cleats 20 across its lower surface, which has corresponding 80 tongue and grooved projections 33 and 34 which join with the corresponding projections from the cleats 13 and 15, so that the same character of joint is produced, either when the leaf is employed, or when the sections 2 and 3 are joined directly together. Diagonal cleats 35 are shown secured to the 85 end sections 2 and 3.

The sides of the reinforcing strips along the adjoining edges of the sections 2 and 3 90 and also of the extra leaf are formed with pairs of grooves such as 21 and 22 in which the ends 23 of a bail 24 on a clamp are adapted to engage or slide when the clamp is being adjusted. The body of the bail is 95 secured to a plate 25 having a lip 26 through which a clamp screw 27 is threaded. In use the clamp is moved with its bail engaged with the reinforcing strips, such as 8 and 9 until the clamp screw 27 can be engaged 100 with a support such as a table top 30, whereupon the screw can be set with its buffer end 28 pressing against the support to hold the parts of the supplemental table tightly 105 clamped to said support and held firmly together. A shoulder plate 31 on the upper end of the clamp plate 25 acts as a guide over the lower surfaces of the strips such as 8 and 9, so that the bail can be adjusted more readily and without binding. In use 110 the sections 2 and 3 are joined together in the manner stated, or they are joined to the

extra leaf and as many clamps such as described are applied to the parts for holding the supplemental top on the support such as a table. As many extra leaves can be employed as desired, the method of construction following the lines indicated above.

The lower surfaces of the parts such as the strips 8 and 9 are covered by felt or other suitable buffing material indicated at 10 32 for the purpose of protecting the surface of the table 30 or other support from becoming scratched or marred. These supplemental table top sections with or without extra leaves provided with intermeshing 15 cleats and projecting tongues are rigidly and securely joined together by the construction described and are held together and upon a table of any size securely and firmly.

In accordance with the patent statutes, I 20 have described the principles of operation of my invention, together with the apparatus which I now consider to represent the best embodiment thereof, but I desire to have it understood that the construction 25 shown is only illustrative, and that the invention can be carried out by other means and applied to uses other than those above set forth within the scope of the following claims.

30 Having described my invention, what I

Copies of this patent may be obtained for five cents each, by addressing the "Commissioner of Patents, Washington, D. C."

claim as new and desire to protect by Letters Patent is:—

1. A supplemental table top, comprising, in combination, top sections having cleats along their meeting edges mortised together, 35 said cleats having longitudinal grooves in their opposite sides and clamps having bail hooks engaging said cleats in said grooves and adapted to hold said sections together upon a table.

2. A supplemental table top, comprising, in combination, top sections having cleats secured thereto along their longitudinal meeting edges provided with interlocking faces and additional cleats secured at an 40 angle to said first mentioned cleats having projecting intermeshing tongues slidably disposed with respect to one another and with respect to said first mentioned cleats.

3. A supplemental table top, comprising, in combination, top sections having cleats secured thereto along their longitudinal meeting edges having mortised intermeshing faces, and additional cleats secured at an 45 angle to said first mentioned cleats having projecting intermeshing tongues.

In testimony whereof I have signed my name to this specification.

EUGENE J. LE CLAIRE.
